UNITED STATES PATENT OFFICE.

FRANK V. BURTON, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ADVERTISING DEVICE.

1,075,009.

Specification of Letters Patent. Patented Oct. 7, 1913.

Application filed August 15, 1911. Serial No. 644,202.

To all whom it may concern:

Be it known that I, FRANK V. BURTON, a citizen of the United States of America, and residing at Bridgeport, in the county of 5 Fairfield and State of Connecticut, have invented a certain new and Improved Advertising Device, of which the following is a specification.

My invention relates to advertising devices and particularly to a device for advertising a series of articles with interchangeable parts, the object of my invention being to provide an attractive display device in which the different parts of a series of 15 articles having interchangeable parts may be readily brought into desired relation to each other, in which position an identification mark such as a catalogue number is revealed by which the particular combination of interchangeable parts is differentiated from other combinations of said parts, thereby to facilitate the discovery of the proper style number by a dealer desiring to purchase any particular combination of 25 the series.

The accompanying drawing, illustrates in a broken elevation, one exemplary embodiment of my invention.

In the form shown the method of display, 30 which may be variously modified, comprises a placard A on which is pivoted a disk B. The articles with interchangeable parts are here exemplified by a series of electric two-part fittings of which one part x^1 , x^2 , x^3 , 35 etc., of any of the fittings may be used with any of the other parts y^1 , y^2 , y^3 , etc., of the series of fittings. To bring these interchangeable parts readily into their various relationships, I arrange illustrations of one 40 element of the various fittings around the periphery of the disk B and the other element of the various fittings in a circle on the base A just outside the disk. Obviously the rotation of the disk brings each x part of 45 the fittings under each y part of the fittings.

To differentiate and identify the fittings in the various relationships of the interchangeable parts, an arbitrary symbol—such as a number, is given to each particular 50 relationship of the interchangeable parts.

Thus for the element y^1 when combined with x^1 the arbitrary number 412 is chosen to identify this particular relationship. For the combination of y^1 with x^2 another arbitrary number is chosen, and so on for each

element of the x series with each element of the y series. In the exemplification of my invention illustrated, these identification marks are arranged in columns C¹, C², C³, etc., extending radially from each y element on the base beneath the disk B. To expose these marks a series of perforations D¹, D², etc., are cut in the disk B radially aligned with each x member of the series of fittings, but spaced different distances from 65 the center of the disk, so that each perforation overlies a different mark in each radial column C as it passes over the same upon the rotation of the disk.

The value of the device is readily appreciated. A dealer desiring to order a particular combination of the interchangeable parts, has but to rotate the disk B upon the placard A until the particular x element is aligned with the particular y element of the 70 combination whereupon the identification mark of this particular combination is displayed through the radially aligned D aperture in the disk.

If a catalogue is used by the manufacturer 80 of the fittings, the corresponding catalogue numbers will ordinarily be employed as the identification marks on the placard A and the dealer is thus saved the trouble of hunting laboriously through a catalogue to find 85 the style number of the particular combination fitting desired. The placard illustrated graphically displays one hundred possible combination fittings. This number may obviously be greatly increased by increasing 90 the number of interchangeable elements illustrated. In this connection it should be pointed out that it is of course unnecessary that precisely the same number of x and y elements be displayed upon the chart, so 95 long as each x element has its corresponding D aperture properly spaced from the center of the disk and each y element has its radial column of identification marks properly spaced apart to correspond with the D 100 apertures.

I claim as my invention:

1. An advertising device for a series of articles with interchangeable parts comprising a member having representations thereon of one part of each of the series of articles and a separate member having representations thereon of another part of each of the series of articles, said members being movable with relation to each other to bring 105 110

- one part of any of the series of articles into predetermined relation to the coöperating part of any of the series of articles, in combination with a series of identification marks for each combination of the coöperating parts and means for displaying the particular mark for each combination when said coöperating parts are brought into predetermined relation to each other.
- 10 2. An advertising device for a series of articles with interchangeable parts comprising a placard having arranged in a circle thereon one part of each of the series of articles, and a disk pivoted on said placard 15 within said circle and having peripherally represented thereon, the coöperating parts of said series of articles, in combination with a series of columns of identification marks on said placard, one for each representation thereon, said disk being perforated to form a series of eight apertures corresponding in number to the parts peripherally represented thereon and spaced 20 radially different distances from the pivotal center of the disk corresponding to the radial spaces between the identification
- marks in each column on the placard, substantially as and for the purpose described.
3. An advertising device for a series of two-part fittings having interchangeable parts, said device comprising a base placard and a disk rotatably mounted thereon, said placard having arranged thereon in a circle outside said disk representations of one part of each of said series of fittings, while said disk has arranged thereon at its periphery representations of the other part of each of said series of fittings in coöperating position, whereby any one part of said series of fittings may be brought into register with any one of the coöperating parts of said series, in combination with identification marks for various combinations of coöperating parts, and means for displaying the same when said parts are in register. 45

In testimony whereof I have signed my name to this specification, in the presence of two subscribing witnesses.

FRANK V. BURTON.
